United States Patent Office.

THOMAS W. BRACHER, OF NEW YORK, N. Y.

Letters Patent No. 91,077, dated June 8, 1869; antedated May 28, 1869.

IMPROVEMENT IN CUTTING HAT-TIPS.

The Schedule referred to in these Letters Patent and making part of the same.

To all whom it may concern:

Be it known that I, THOMAS W. BRACHER, of the city, county, and State of New York, have invented a new and useful Improvement in Cutting Tips for Hats and Caps; and I do hereby declare the following to be a full, clear, and exact description thereof, which will enable those skilled in the art to make and use the same, reference being had to the accompanying drawing, forming part of this specification, in which drawing—

Figure 1 represents a transverse section of the apparatus which I use in carrying out my invention.

Figure 2 is a plan or top view thereof.

Figure 3 is a diagram explaining my method of cutting.

Similar letters indicate corresponding parts.

This invention consists in a new method of cutting out the tips for hats and caps, by first folding the fabric into a number of layers, of sufficient width for one or more tips, then fastening said layers together by stitching, or otherwise, and finally cutting through the whole pile by means of a knife, which is forced through the pile by a suitable press.

The devices which I use in carrying out my invention are illustrated in the drawing, where A represents a box, of wood, or any other suitable material, open at one end, and provided at the opposite end with a standard, B, from which extends an arm, C, over the whole length of the box, as shown in fig. 2. This arm is provided with a slot, a, through which I pass the fabric to be folded and cut.

The box A is made of a width equal to the single or multiple major axis of the tips to be cut, (said tips being in the shape of an ellipse,) and may be so constructed that its width can be adjusted for tips of different size or shape.

Into this box is fitted a series of flat plates, b, of tinned sheet-iron, or other suitable material, and these plates are provided with holes c, as shown.

The end of the fabric being drawn through the slot a in the arm C, is spread on the bottom of the box, one of the plates, b, is placed on, the fabric is folded over this plate, and a second plate is placed on, the

fabric is folded over this plate, and a third plate is put on, and so forth, until the entire piece of the fabric is arranged in the box, as indicated in red outlines in fig. 1.

During the operation of folding, however, the plates, lying between the layers, at or near the bottom of the pile, can be drawn out and used over and over again, so that a comparatively small number of plates is sufficient to complete the operation of folding.

After the fabric has thus been folded, all the plates, with the exception of that on top, are withdrawn, and the pile is fastened by stitching through the holes c, or by any other suitable means, and after the last plate has been removed, the pile is taken out of the box A and cut.

The operation of cutting is effected by a knife, the shape of the cutting-edge of which is represented by the curved lines in fig. 3, and which is so formed that it can be placed under a press and forced through the whole pile.

I am aware that tips for hats and caps are cut out by knives or scissors, but only few at a time, and without folding the fabric, and fastening the pile, as above described.

Having thus described my invention,

What I claim as new, and desire to secure by Letters Patent, is—

1. The mode of preparing fabric, adapting it for being cut into tips for hats and caps, by folding said fabric in continuous layers, with the interposed perforated plates c, then removing said plates, excepting the upper one, and through the perforations thereof uniting the entire series of folds, and thereby form a completed pile, to be subjected to the knife, as herein described.

2. Also, for the purpose of the above mode of preparing fabric as stated, the open-end box A, and the elevated slotted arm C, combined and operating as represented and described.

T. W. BRACHER.
